UNITED STATES PATENT OFFICE

157,731

BOTTLE CASE

Daniel R. Branen, New York, N. Y., assignor to Greatrex Ltd., New York, N. Y., a corporation of New York

Application June 11, 1948, Serial No. 146,919

Term of patent 14 years

(Cl. D58—2)

To all whom it may concern:

Be it known that I, Daniel R. Branen, a citizen of the United States, residing at New York, in the county of New York and State of New York, have invented a new, original, and ornamental Design for Bottle Case, of which the following is a specification, reference being had to the accompanying drawings, forming part thereof.

Fig. 1 is a front elevational view of a bottle case showing my new design, and

Fig. 2 is a side elevational view thereof.

I claim:

The ornamental design for a bottle case, as shown.

DANIEL R. BRANEN.
